UNITED STATES PATENT OFFICE.

JOHN OBERDIER, OF MOUNT GILEAD, OHIO.

LIFTING-JACK MECHANISM FOR MOTOR-VEHICLES.

1,226,242.

Specification of Letters Patent. Patented May 15, 1917.

Application filed March 20, 1916. Serial No. 85,490.

To all whom it may concern:

Be it known that I, JOHN OBERDIER, a citizen of the United States of America, residing at Mount Gilead, in the county of Morrow and State of Ohio, have invented certain new and useful Improvements in Lifting-Jack Mechanism for Motor-Vehicles, of which the following is a specification, reference being had therein to the accompanying drawing.

This invention relates to a lifting jack mechanism for motor vehicles, and has for its principal object the production of a simple and efficient means for lifting the motor car entirely from the supporting surface by the operation of the engine.

Another object of this invention is the production of a lifting jack mechanism for motor vehicles which has a plurality of cables connected to a drum so that as this drum is operated by the running of the engine the cables will be wound upon the drum so as to rotate certain pulleys which in turn having jacks connected thereto will move the jacks to operative positions for lifting the motor car from the supporting surface.

With these and other objects in view this invention consists of certain novel combinations, constructions, and arrangements of parts as will be hereinafter fully described and claimed.

In the accompanying drawings:

Figure 1 is a top plan view of the lifting jack mechanism, together with the brake, as applied to a motor car.

Fig. 2 is a rear elevation of the device.

Fig. 3 is a vertical section taken on the line 3-3 of Fig. 2, looking in the direction of the arrow and illustrating the jack member in a lowered position as it appears in use.

Fig. 4 is a section taken on the line 4-4 of Fig. 3.

Referring to the accompanying drawings by numerals, 1 designates the frame of the motor car which is constructed of a plurality of longitudinally extending side beams 2 which are supported upon the bolsters 3 having the springs 4 which are in turn connected to the rear axle 5 supported by the rear wheels 6. The forward ends of these side beams 2 are connected in any suitable manner to the forward axle 7 carried by the forward wheel 8. The beams 2 are connected intermediate their ends by the cross-bars

9, 10, and 11. The crank shaft 12 is intended to be used with the engine, any form of which may, of course, be employed in connection with this device without departing from the spirit of the invention and has mounted upon its forward end the friction pulley 13. The intermediate pulley 14 is carried by the bracket 14' supported by one of the side beams 2, as shown in Fig. 1. This intermediate friction pulley 14 also engages the friction pulley 15 carried by the forward end of the operating shaft 16, which shaft 16 passes along adjacent one of the side beams 2 and is carried in any suitable manner by the bars 9, 10, and 11. The grooved sleeve 17 is slidably mounted, although keyed upon the shaft 16 and has the beveled gear 18 at one end. Therefore, it will be seen that as the engine is in operation and rotary motion is imparted to the shaft 12 rotary motion will be imparted through the frictional pulleys 13, 14, and 15 to the shaft 16 so that rotary motion will also be imparted to the beveled gear 19 by means of the sleeve 17 keyed upon the shaft 16. The stem 20 is carried by one of the side beams 2 as shown in Fig. 1, and has the spool 21 rotatably mounted thereon. This spool 21 is provided with a pinion 22 which meshes with the pinion 23 carried upon the cross bar 10. The beveled gear 25 is in turn connected to this pinion 23, as also shown in Fig. 1.

When the shaft 16 is in operation and the sleeve 17 is moved along the shaft so as to permit the beveled gear 18 thereof to engage the beveled gear 25 it will be seen that rotary motion will be imparted through the pinions 22 and 23 to the spool 21. A forwardly extending operating cable 26 and a rearwardly extending operating cable 27 are secured to the spool 21 and extend therefrom so as to have the branch cables 28 connected thereto. These branch cables 28 pass between the spools 29 carried upon the bars 9 and 11 so that the branch cables 28 will be held so as to be positioned in a central position with respect to the central plane of the frame, whereby the operating cables 26 and 27 will be directed so as to wind evenly upon the spool 21. There are also provided guide spools 30 upon the side beams 2 so as to permit the branch cables 28 to pass around these guide spools 30 where by the cables in passing around these guide spools 29 and 30 will be prevented from

spreading over too great a territory when in use.

The jack and pulley housings comprise a pair of sections having the side flanges 32 formed thereon through which the bolts and nuts 33 being applied therethrough will hold the sectional housings 31 in assembled positions. These sectional housings 31 are provided with enlarged openings 34 formed therein so as to permit the axles 5 and 7 to pass through the housings for fixedly supporting the same. The branch cables 28 after passing around the guide spools 30 pass into the housings 31 as shown in Fig. 1, whereby the ends of these branch cables 28 will pass about the operating pulleys 36 carried within the housings 31. These housings 31 are also provided with aligned threaded apertures 37 and 37' so as to permit the externally threaded jack stems 38 to pass through these apertures 37 and 37' and through the central threaded bore 39 formed in the operating pulley 36.

Upon the lower end of the jack stem 38 there is carried a caster as shown in Fig. 3.

When it is desired to lift or jack up the motor vehicle the engine, of course, should be running so as to impart rotary motion to the shaft 16 as hereinbefore set forth. As the gear 18 will impart rotary motion to the gear 15, and pinions 22 and 23 to the spool 21, the cables 26 and 27 will be wound thereon. As the cables 28 are drawn toward and upon the spool 21 they, of course, will rotate the operating pulleys 36 and this action will cause the operating pulleys to move the jack stem 38 downwardly from the lower portions of the housings 31. Upon the continued rotation of the operating pulleys 36 the casters 41 coming into engagement with the floor of the garage, the road, or any other supporting surface will, of course, lift the motor car so that the entire weight thereof will be supported by these jacks. By this construction it will be seen that if at any time it is desired to work upon the tires, or when the car is not in use it is desired to remove the weight from the tires and thus prolong the life of the tires, these jacks are to be used. As soon as it is desired to cause the stems to again support the weight of the car and move the jacks from operation the sleeve 17 may be moved so as to cause the beveled gears to be moved to a neutral position and at this time the weight of the car will cause the jack stems to be moved upwardly through the housings and thus operate the pulleys 36 so as to unwind the cables 28 therefrom. From the foregoing description it will be seen that a very simple and efficient device has been constructed which is formed so as to constitute a lifting jack for motor vehicles which will easily lift cars by the running of the engine which will impart ro-

tary motion through various gears and shafts to the winding spool, thus causing the cables to be wound thereon, which action by rotating the operating pulleys will drive the jack stems into the ground for the purposes above set forth. 70

What is claimed is:—

1. In a device of the class described, the combination of a frame comprising a pair of side beams, a plurality of transversely extending bars connected to said beams, axles carried by the ends of said beams, a stem carried by said frame, a spool rotatably carried upon said stem, a pinion connected to said spool, a pinion mounted upon one of said bars, a beveled gear keyed to said last-mentioned pinion, a shaft carried by a plurality of said bars, means for rotating said shaft, a sleeve slidably mounted upon said shaft and being keyed thereto, a beveled gear supported by said sleeve, said beveled gear being adapted to be moved into engagement with said first-mentioned beveled gear, whereby as said shaft is rotated rotary motion will be imparted by said beveled gears and pinions to said spool, housings carried by said axles, pulleys carried within said housings, jack stems connected to said pulleys, cables connecting said pulleys to said spool, whereby as rotary motion is imparted to said spool said cables will be wound thereon so as to operate said pulleys and thus cause said jack stems to be moved into an operative position for lifting and carrying said frame. 85

2. In a device of the class described, the combination of a frame comprising a pair of side beams, a plurality of transversely extending bars connected to said beams, axles carried by the ends of said beams, a stem carried by said frame, a spool rotatably carried by said stem, a pinion connected to said spool, a pinion mounted upon one of said bars, a bevel gear keyed to said last-mentioned pinion, a shaft carried by a plurality of said bars, means for rotating said shaft, a sleeve slidably mounted upon said shaft and being keyed thereto, a bevel gear supported by said sleeve, said bevel gear being adapted to be moved into engagement with said first-mentioned bevel gear, whereby as said shaft is rotated rotary movement will be imparted by said bevel gears and pinions to said spool, and jack means carried by said frame and coöperating with said spool, whereby said jack means may be moved downwardly into engagement with a support for supporting said frame. 110

3. In a device of the class described, the combination of a frame comprising a pair of side beams, a plurality of transversely extending bars connected to said beams, axles carried by the ends of said beams, a stem carried by said frame, a spool rotatably carried by said stem, a pinion connected 125

- to said spool, a pinion mounted upon one of said bars, a bevel gear keyed to said last-mentioned pinion, a shaft carried by a plurality of said bars, means for rotating said 5 shaft, a sleeve slidably mounted upon said shaft and being keyed thereto, a bevel gear supported by said sleeve, said bevel gear being adapted to be moved into engagement with said first-mentioned bevel gear, whereby 10 as said shaft is rotated rotary movement will be imparted by said bevel gears and pinions to said spool, jack stems having casters carried by said frame, and means connecting said stems to said spool, whereby 15 upon the movement of said spool said stems may be driven downwardly into engagement with a support for movably supporting said frame.
4. In a device of the class described, the 20 combination of a frame comprising a pair of side beams, a plurality of transversely extending bars connected to said beams, axles carried by the ends of said beams, a stem carried by said frame, a spool rotatably 25 carried by said stem, a pinion connected to said spool, a pinion mounted upon one of said bars, a bevel gear keyed to said last-mentioned pinion, a shaft carried by a plurality of said bars, means for rotating said 30 shaft, a sleeve slidably mounted upon said shaft and being keyed thereto, a bevel gear supported by said sleeve, said bevel gear being adapted to be moved into engagement with said first-mentioned bevel gear, whereby 35 as said shaft is rotated rotary movement will be imparted by said bevel gears and pinions to said spool, closed housings carried upon said axles, said housings having side openings, grooved pulleys carried entirely within said housings, jack stems passing 40 through said housings and carried by said pulleys, cables connected to said spool and passing through the openings of said housings and being secured to said grooved
- pulleys and wound thereon, whereby upon 45 the movement of said pulleys said cables will turn said pulleys so as to move said jack stems into engagement with a support for supporting said frame.
5. In a device of the class described, the 50 combination of a frame comprising a pair of side beams, a plurality of transversely extending bars connected to said beams, axles carried by the ends of said beams, a stem carried by said frame, a spool rotatably 55 carried by said stem, a pinion connected to said spool, a pinion mounted upon one of said bars, a bevel gear keyed to said last-mentioned pinion, a shaft carried by a plurality of said bars, means for rotating said 60 shaft, a sleeve slidably mounted upon said shaft and being keyed thereto, a bevel gear supported by said sleeve, said bevel gear being adapted to be moved into engagement with said first-mentioned bevel gear, whereby 65 as said shaft is rotated rotary movement will be imparted by said bevel gears and pinions to said spool, housings positioned upon said axles, each of said housings comprising an upper and lower section, said 70 sections being clamped together so as to fix said housings upon said axles, said housings provided with alined vertical openings and with side openings, grooved pulleys positioned entirely within said housings, jack 75 stems passing through said vertical alined openings and through said pulleys, cables connecting said cables to said spool, said cables passing through said side openings, whereby said spool may be rotated so as to 80 cause said cables to turn said pulleys and thereby move the jack stems into engagement with a support for carrying said frame.

In testimony whereof I hereunto affix my 85 signature.

JOHN OBERDIER.
